COMBINED "THERMOS" AND CIGARETTE PACKAGE HOLDER FOR USE IN A VEHICLE

William L. Housman, 419 Coyne Ave., Miami, Okla.

Filed Nov. 3, 1959, Ser. No. 58,192

Term of patent 14 years

(Cl. D58—26)

Figure 1 is a side view of a combined "Thermos" and cigarette package holder for use in a vehicle embodying my new design;

Figure 2 is a front view thereof; and
Figure 3 is a top plan view thereof.

The "Thermos" and cigarette package shown in broken lines in Figure 1 are for illustrative purposes only.

The side not shown is substantially the same as the side shown.

I claim:

The ornamental design for a combined "Thermos" and cigarette package holder for use in a vehicle, as shown.
